MASSACHUSETTS.

MEANS FOR POSITIONING TRANSFERRED FABRICS ON KNITTING MACHINES.

Application filed June 19, 1928. Serial No. 286,519.

This invention has for its object to facilitate that operation, customary in the normal use of knitting machines, whereby a fabric, knit on one machine, is transferred to the 5 needles of another machine, on which the knitting of the fabric is completed.

As an example of a fabric thus knit on two machines may be mentioned a stocking whose leg, ankle and foot are knit on one machine as a continuation of a tubular ribbed top which has been knit on another machine; the ribbed fabric being removed from the second machine and the end loops thereof being transferred to the needles of the first machine, 15 on which the knitting of the leg begins as an integral continuation of the ribbed top. Other examples may be cited involving the transfer from one machine to another of different kinds of circular and flat knitted 20 fabric.

The transfer operation is usually effected by means of a transfer device by which the terminal loops, selvage loops, or some other series of loops, of a fabric knit on one machine may be strung on the needles of another machine. Where the transfer is effected onto a circular machine, the transfer device usually comprises a circularly arranged 25 series of quills adapted to fit over the leveled needles of the circular machine. In the transferring operation, the needles penetrate loops held open by the quills and engage such loops in the needle hooks.

In the transferring operation it is required 30 that the loops shall be moved down over the needle shank a definite distance, whether such needles are of the spring beard type or of the latch type. Such required positioning of the loops cannot be effected automatically by the 35 transfer device. In the case of latch needles, most of the cooperating sinkers or web 40 holders are, at any given position of the needle cylinder, in a position to obstruct the slipping of the loops to the low position desired, and hand adjustment of the transferred 45 fabric, accompanied by a rotation of the needle cylinder, is required to accurately position the complete circle of loops.

The object of this invention, more specifically stated, is to effect, automatically, the proper positioning on the needles of the loops of the transferred fabric, and to accomplish this result without danger of cutting the fabric.

A preferred embodiment of the invention, 55 showing an adaptation of the invention to a machine provided with latch needles and sinkers, is shown in the accompanying drawings, in which—

Fig. 1 is a sectional elevation through a 60 needle cylinder and sinker dial, with the invention applied thereto.

Fig. 2 is a diagram showing the path of the 65 noses of the sinkers or web holders in one rotation of the machine.

Fig. 3 is a front view of the cam for depressing the transferred fabric to the desired level with respect to the needles.

Fig. 4 is a plan view of said cam.

Fig. 5 is a side elevation of a needle, its 70 cooperating sinker, and a section of transferred fabric, the latter being in the position which it assumes as a result of the operation of the ordinary transfer device.

Fig. 6 is a side elevation, partly in section, of a needle, a cooperating sinker, said cam and a section of the transferred fabric 75 in the position to which it is depressed by the action of said cam.

The needle cylinder or other needle carrier 80 *a* is grooved to receive the independent needles *b*, which are movable up and down in a normal knitting wave by cams not shown. Fastened to the needle cylinder is the sinker dial *c*, which carries the sinkers or web holders *d*, which are movable radially, by means of a cam *f*, in the usual manner, to cooperate 85 with the needles to form stitches. The sinkers, throughout the larger part of the circumference, or length, of the needle bank, 90 are in the advanced (inward) position shown in Fig. 5; but from a point following the rise of the needles to take yarn to a point in advance of the depression of the needles to their lowest level to knit, the sinkers are in 95 the withdrawn (outward) position shown in Fig. 6. The broken line *x*—*y* in Fig. 2 shows, in a circular machine, the in-and-out wave described by the points of the holding-down hooks or noses *e* of the sinkers *d* in a 100 complete rotation.

A swinging frame carries the usual latch ring *g* and also the usual platform *h* on which are mounted a clamp and cutter (not shown) adapted to clamp and cut yarn, which is fed from yarn carriers accommodated in a throat formed in the latch ring; one of the 105 yarn carriers, *i*, being shown in Fig. 1.

In the operation of transferring a knitted fabric, the pivoted latch ring *g*, with the platform *h*, is lifted out of the way, the needles *b* are leveled and the transfer device (not shown) is applied. Since all of the sinkers *d* except those in the wave of retraction indicated at *y*, Fig. 1, have their hold-down hooks or noses *e* between the needles, as shown in Fig. 5, it is obvious that the transfer device cannot depress the loops of the transferred fabric *w* below the plane of the noses of the sinkers, that is, below the position shown in Fig. 5. It is unsafe to rely upon the subsequent knitting movement of the needles to position the fabric in proper relation to the sinkers. It is, therefore, customary for the operator to insert his hand within the needle cylinder and pull down the fabric, while rotating the needle cylinder, so that the transferred loops are all brought to the position, shown in Fig. 6, which will insure their being in proper position with relation to the noses of the sinkers at the beginning of the immediately following knitting operation. This is a difficult operation, involves a certain delay, and in the absence of care or skill may not be properly performed.

In order to insure the pulling down of all the transferred loops to the proper level, and to effect this pulling down operation automatically, we mount, on the platform *h*, a cam plate *k* which is positioned just back of, and spaced from, the needles, and opposite the throat of the latch ring and extends along a part of that arc of travel of needles and sinkers during which the sinkers are in the retracted position indicated by the line *y* and shown in Fig. 6. The lowest part of the lower convex cam edge of cam plate *k* is somewhat below the level of the noses *e* of sinkers *d*. The upper level of cam plate *k* should not be high enough to obstruct delivery of yarn by a yarn carrier *i* either at transferring or at the normal knitting position of the needles. The clearance between the lower cam edge of cam plate *k* and the upper edges of the arms of the sinkers should be sufficient to accommodate the transferred fabric. Since cam plate *k* acts upon only that part of the fabric which, at any given time, is opposite retracted sinkers, the edge of the transferred fabric is free to be pushed down the needle shanks to the correct position.

We are aware that a fixedly mounted cam for depressing transferred fabric positioned like the cam plate *k*, to perform in part the same work, has been used by others. This invention improves on that device by avoiding any danger of damage to the transferred edge when there is not enough clearance between the cam and the top edges of the withdrawn web holders, whatever may be the resistance to motion on the needles or the thickness of the transferred fabric, thus avoiding cutting of the transferred fabric if the ma-

chine should be used for a thicker or different kind of transferred section from that for which it was designed and adjusted. By making the cam *k* resiliently yielding, a wider range of work can be better performed on the machine; and the cam *k* can also operate in aid of knitting on machines in which the first few courses after transfer and resumed knitting do not securely take under the hooks of advancing web holders, as may happen when the yarns are stiff and intractable, or the transferred section too light to aid in holding down the fabric by gravity or tensile stress. The resiliently held cam *k* may be relied upon to keep the last course down on the needles and a few previously knit courses well down on the web holders at the knitting wave throughout operation of the machine.

In our invention, the cam plate *k* is not directly secured to platform *h*, but is so fixedly mounted on platform *h* or other convenient support that, while it tends to assume the lowest position that is desirable, it is capable of yielding in an upward direction in case the fabric offers a more substantial resistance to depression than is incidental to the slight resistance afforded by the thicker part of the needle along which it is being pushed by the cam. Preferably the cam plate *k* is made in the form of a horizontal plate having a downward projecting flange whose lower edge is convexly shaped to give it the proper cam contour. The horizontal plate is secured to the under side of a leaf spring *m* which, at its rear end, is bent downward and forward to form an end extension which is secured to platform *h* by means of screws or other fasteners *n*. To facilitate the insertion of the screws the upper reach of the spring leaf is provided with holes *o* through which the screws may be inserted. The front of the spring leaf is secured to the horizontal member of the cam plate by means of rivets *r*. Extending through the spring leaf and cam plate is an adjusting screw *s*, which is held in adjusted position by means of a nut *t*. By this adjusting means, the vertical position of the cam may be adjusted to the exact position that is found to be the most desirable in view of the thickness of the transferred fabric. Very accurate adjustment is, however, not required, since, if the cam is so adjusted as to be capable of assuming a somewhat lower position than is required, it will yield upward against the pressure of the fabric.

While it is preferred that the cam plate *k* and the leaf spring *m* shall be separate members secured together, it is practicable to make these parts in one integral piece. This would require no other change in the described construction except, of course, the omission of the connecting rivets *r*.

It sometimes happens, in ordinary knitting, especially where the loops do not fairly tight-

ly engage the needles, that the fabric creeps above the level required to insure the proper cooperative action of the sinkers. With our improvement, this upward creeping action of the fabric will be prevented.

Having now fully described our invention, what we claim and desire to protect by Letters Patent is:

1. In a knitting machine, the combination with relatively rotatable needles and sinkers, and means for advancing and retracting the sinkers, of a relatively non-rotatable support, and a device adapted to engage fabric looped on the needles and effect a sliding of the needle-engaging loops of such fabric along the needle shanks into predetermined positions relative to said sinkers while the latter are in retracted position, said device being yieldingly mounted on said support and adapted to recede from its normal position against resistance of the fabric.

2. In a knitting machine, the combination with relatively rotatable needles and sinkers, and means for advancing and retracting the sinkers, of a relatively non-rotatable support, and a device adapted to engage fabric looped on the needles and effect a sliding of the needle-engaging loops of such fabric along the needle shanks into predetermined positions relative to said sinkers while the latter are in retracted position, said device comprising a spring mounted on said support and adapted to yieldingly resist displacement by the fabric from its normal position.

3. In a knitting machine, the combination with relatively rotatable needles and sinkers, and means for advancing and retracting the sinkers, of a relatively non-rotatable support, a device adapted to engage fabric looped on the needles and effect a sliding of the needle-engaging loops of such fabric along the needle shanks into predetermined positions relative to said sinkers while the latter are in retracted position, said device being yieldingly mounted on said support and adapted to recede from its normal position against resistance of the fabric, and means to adjust said device to predetermine its normal position.

4. In a knitting machine, the combination with relatively rotatable needles and sinkers, and means for advancing and retracting the sinkers, of a relatively non-rotatable device adapted to engage fabric looped on the needles and effect a sliding of the needle-engaging loops of such fabric along the needle shank into predetermined positions relatively to said sinkers while the latter are retracted,

a relatively non-rotatable support, and a flexible and elastic connection between said support and said device.

5. In a knitting machine, the combination with relatively rotatable needles and sinkers, and means for advancing and retracting the sinkers, of a relatively non-rotatable support, a cam adapted to engage fabric looped on the needles and effect a sliding of the needle-engaging loops of such fabric along the needle shanks into predetermined positions relatively to said sinkers while the latter are in retracted position, and a tension device mounted on said support and adapted to yieldingly hold said cam in its operative position.

6. In a knitting machine, the combination with relatively rotatable needles and sinkers, and means for advancing and retracting the sinkers, of a relatively non-rotatable support, a device adapted to engage fabric looped on the needles and effect a sliding of the needle-engaging loops of said fabric along the needle shanks into predetermined positions relatively to said sinkers while the latter are in retracted position, a tension device mounted on said support and adapted to yieldingly hold said device in its operative position, and an adjustable member adapted to be operated to predetermine the position in which said device is normally held by said tension device.

7. In a circular knitting machine, the combination with a rotatable circle of needles and sinkers, means to advance and retract the sinkers, and a non-rotatable platform within the circle of needles and sinkers, of a radially extending leaf spring secured at its inner end to said platform, a plate secured to the outer end of said spring and having a depending part extending inside of and spaced from the path of rotation of the needles and provided with a lower cam edge adapted to engage fabric looped on the needles and effect a sliding of the loops of said fabric along the needle shanks into predetermined position relatively to said sinkers while the latter are in retracted position, said spring yieldingly pressing said plate downward, and means providing an abutment which prevents the plate being moved downward beyond a predetermined position.

In testimony of which invention, we have hereunto set our hands, at Philadelphia, Pennsylvania, on this 18th day of June, 1928.
